UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ATTACHMENT-PLUG.

1,352,817.

Specification of Letters Patent. Patented Sept. 14, 1920.

Application filed April 4, 1917, Serial No. 159,602. Renewed November 8, 1917. Serial No. 200,996.

To all whom it may concern:

Be it known that I, CHARLES J. KLEIN, a citizen of the United States, residing at Milwaukee, in the county of Milwaukee and 5 State of Wisconsin, have invented new and useful Improvements in Attachment-Plugs, of which the following is a full, clear, concise, and exact description, reference being had to the accompanying drawing, forming 10 a part of this specification.

This invention relates to attachment plugs and similar devices and more particularly to contact anchoring means therefor.

In certain devices, as in the case of attachment plugs where molded insulating parts are employed to carry contacts, considerable 15 difficulty has been experienced in rigidly attaching the contacts thereto, and the present invention has among its objects to provide 20 simple and effective means for this purpose.

A further object is to facilitate and expedite the securement of the contacts to the insulating parts and to reduce the cost of such operation.

25 Other objects and advantages will hereinafter appear.

In the accompanying drawing, wherein is illustrated an embodiment of the invention,

Figure 1 is a plan view of an attachment 30 plug cap, and,

Fig. 2 is a side elevational view, partly in section, of the same.

Referring to the drawing, the cap comprises a molded insulating base 1 centrally 35 perforated and provided with an annular rim 2 and a pair of projecting contacts 3 and 4 each having an offset portion 5 to be secured to and definitely positioned upon said base.

40 The securing or anchoring means for said contacts comprises a pair of metal inserts 6 molded in said base in a parallel relation and equidistant from the center of the base.

Each insert is provided with diverging 45 shoulder 7 for securely anchoring the same within the base and is further provided with a pair of integral lugs 8, 9 suitably spaced and projecting beyond the surface of the base to engage snugly within a pair of similarly 50 spaced openings in the offset portion of one contact. The lug 8 extends through the contact portion 5 and is riveted thereto for insuring permanent and rigid attachment of the contact to the base, while the lug 9 55 insures against lateral displacement of the

contact. The latter lug need not be riveted although it might be riveted similarly to the former lug, if so desired.

The above described anchoring means serves not only to insure accurate positioning and rigid securement of the contacts, but also facilitates attachment thereof, since the projecting lugs assist in locating the contact in the desired position between the opening in the base and the rim. Thereafter 65 one or both lugs may be riveted to the contact for permanently securing the same in position.

What I claim as new and desire to secure by Letters Patent is:

1. The combination with a molded insulating base and a contact to be secured thereto, of a metal insert molded in said base and having integral lugs projecting from said base and engaging with said contact at 75 spaced points to definitely position the same, and one of said lugs being utilized to rivet said contact to said base.

2. The combination with a molded insulating base and a contact to be secured thereto, 80 said contact having an offset portion provided with spaced openings, of a metal insert molded in said base and provided with integral lugs projecting from said base and snugly fitting the openings in the offset portion of said contact, one of said lugs projecting through said offset portion and being riveted for anchoring of said contact.

3. The combination with a molded insulating base and a contact to be secured thereto, 85 of a metal insert molded in said base, said contact being secured to said insert at a given point and said insert having an integral lug engaging said contact at a spaced point for steadyng the same.

4. The combination with an attachment plug cap comprising a molded insulating base having a central opening and a concentric rim, and a contact having an offset portion to fit said insulating base between its central opening and rim, of a metal insert molded in said base and provided with spaced lugs projecting from said base for interlocking engagement with the offset portion of said contact and one of said lugs 105 penetrating said offset portion and being riveted thereto.

5. An attachment plug cap comprising a molded insulating base, a metal insert molded therein and having a lug projecting 110

therefrom and a contact comprising perpendicularly disposed portions, one of said portions being riveted to said base by said lug and the other projecting away from said base, said contact and one of the other of said elements having engaging parts to maintain said contact in a definite position on said base.

6. An attachment plug cap comprising a molded insulating base, a contact having an offset portion, a metal insert molded in

said base and projecting therefrom into said offset portion of said contact, said contact portion and said insert having abutting faces insuring definite positioning of said contact on said base and said insert having a portion affording a rivet to secure said contact to said base.

In witness whereof, I have hereunto subscribed my name.

CHARLES J. KLEIN.
